UNITED STATES PATENT OFFICE.

WILLIAM J. ESTES, OF PASCO, WASHINGTON.

WIRE-STRETCHER.

No. 915,756.

Specification of Letters Patent. Patented March 23, 1909.

Application filed March 9, 1908. Serial No. 420,103.

To all whom it may concern:

Be it known that I, WILLIAM J. ESTES, a citizen of the United States, residing at Pasco, in the county of Franklin and State 5 of Washington, have invented certain new and useful Improvements in Wire-Stretchers; and I do declare the following to be a full, clear, and exact description of the invention, such as will enable others skilled in 10 the art to which it appertains to make and use the same, reference being had to the accompanying drawings, and to the figures of reference marked thereon, which form a part of this specification.

15 My invention relates to wire stretchers and has for its object to provide a device of this class which is simple in construction, cheap to manufacture, strong, durable and efficient.

20 A further object of my invention is to provide a wire stretcher which is so constructed and arranged that it will allow the wire to untwist while the same is being stretched in such manner that all twists and kinks are 25 removed from the wire during the course of stretching the same.

With these objects in view my invention consists in the novel construction of the rack, and my invention also consists in certain other novel features of construction and 30 in combinations of parts, all of which will be first fully described and afterward pointed out in the appended claims.

Referring to the accompanying drawings: 35 Figure 1 is an elevation illustrating the wire stretcher in upward position. Fig. 2 is a top plan view of the same, and Fig. 3 is a vertical sectional view taken on line 3—3 of Fig. 1.

40 Like numerals of reference indicate the same parts throughout the several figures in which:

1 indicates the rack bar which as shown in Fig. 3 is circular in cross section, the rack 45 teeth 2 being frustum shaped, said rack teeth being substantially a series of frustums.

50 3 indicates the slide or sleeve through which the rack bar 1 passes, said slide or sleeve 3 being provided with a boss or projection 4 (Fig. 2) to which the clamp 5 is connected by means of a swivel 6 and link 7, the clamp 5 comprising two sections 8 and 9, the lower section 9 being pivoted to 55 the section 8 at 10 and being provided with a series of serrations or teeth 11 as shown in

Fig. 1, the wire 12 being gripped between the serrated surface 11 and the contiguous surface of the member 8 in such manner that the strain on the wire 12 always tends 60 to cause the serrated surface 11 to bite into the wire in order to secure and hold the same against slipping.

14 indicates the pawls or dogs which engage the rack bar 1, said pawls being provided with handles 15 so that the rack engaging portion 16 can be lifted out of engagement with the rack bar, said pawls 14 being carried in a bifurcated lever 17 as shown in Figs. 1 and 3, the portion 18 of said lever 70 between the two pawls 14 engaging the sleeve or slide 3 for moving said slide along the rack bar 1.

Having thus described the several parts of my invention its operation is as follows: In 75 order to stretch a wire the rack bar 1 is secured permanently by means of the hook 19 on the end thereof. The wire 12 to be stretched is inserted within the clamp 5, as shown in Fig. 1, and the lever 17 is operated 80 in such manner that the lower pawl 14 engages one of the frustum shaped rack teeth 2 causing the lever to fulcrum at 20 and the portion 18 of the lever 17 to engage the sleeve or slide 3, thus drawing the slide or sleeve 85 along the rack bar the distance of one tooth. The lever is then moved in the opposite direction which causes the upper pawl 14 to engage the succeeding frustum shaped rack teeth causing the lever to fulcrum at 21, and 90 the portion 18 of said lever to engage the sleeve or slide 3 and move same over the rack bar the distance of one tooth. Successive operations of the lever 17 as just described draw the clamp 5 and wire 12 toward the 95 hook 19 thus stretching the wire to any degree of tautness.

It will be noticed that the entire sleeve 3, pawls 14 and lever 17 can be rotated on the rack bar 1 in such manner that the lever can 100 be operated in the most convenient position and in such manner that all twist will be removed from the wire during the operation of stretching the same, as the frustum shaped form of the rack teeth allows the rack bar to 105 rotate within the sleeve or slide 3 while the lever 17 is being operated, or the lever, pawls, slides or sleeves 3 can be rotated on the frustum shaped rack teeth while the lever 17 is being operated in order to stretch 110 the wire.

Having thus fully described my invention

what I desire to secure by Letters Patent of the United States is,—

1. A wire stretcher comprising a rack bar having a series of frustum shaped teeth, said rack bar being constructed in such manner that the said teeth are round in cross section, a slide or sleeve carried on said bar and rotatable thereon, a wire clamp carried on said slide or sleeve, a swivel between said clamp and said slide or sleeve, said clamp being rotatable relatively to the said rack bar, a lever and two pawls fulcrumed on said lever, said lever and pawls being mounted on said rack bar in such manner that the said slide or sleeve is moved by said lever.
2. A wire stretcher comprising a rack bar having a series of teeth thereon, said teeth being circular in cross section, a slide or

sleeve carried on said rack bar in such manner that said slide or sleeve is rotatable on said rack bar, a lever and means associated therewith for engaging the teeth of said rack bar to move said sleeve or slide on said rack bar, and a clamp carried by said slide or sleeve and a connection between said clamp and said slide or sleeve, the whole arranged in such manner that the said slide or sleeve is rotatable relative to the said clamp and rack bar, and the said clamp is rotatable relative to the said slide and the said rack bar.

In testimony whereof, I affix my signature, in presence of two witnesses.

WILL J. ESTES.
